Patented May 17, 1921.

FIG. 1.

FIG. 2.

FIG. 4

FIG. 3

Salomon Vos Inventor
By his Attorney
Charles G. Hensley.

UNITED STATES PATENT OFFICE.

SALOMON VOS, OF BROOKLYN, NEW YORK.

BRUSH FOR MUCILAGE AND PASTE BOTTLES.

1,378,636.

Specification of Letters Patent. Patented May 17, 1921.

Application filed July 6, 1920. Serial No. 394,058.

To all whom it may concern:

Be it known that I, SALOMON Vos, a citizen of the United States, and a resident of the borough of Brooklyn, in the city and State of New York, have invented certain new and useful Improvements in Brushes for Mucilage and Paste Bottles, of which the following is a specification.

My invention relates to a simple brush 10 adapted for use on mucilage or paste bottles or jars. The object of my invention is to provide a bottle or jar cap having a brush extending therethrough and slideable therein, the brush being held in any desired position by friction. When the cap and brush are applied to a bottle or jar the cap is adapted to close the top thereof and to support the brush so that the lower or bristle end of the brush dips into the mucilage, 20 paste or other material in the bottle or jar. As the liquid or paste is consumed and its level decreases, the brush is moved down in relation to the cap in order that the brush will dip to the desired extent into the liquid 25 or paste without allowing the part of the brush above the bristles to dip into the liquid or paste. I am aware that caps with adjustable brushes have heretofore been proposed or used but the object of the present 30 device is to provide a brush which will slide very smoothly in the cap and which nevertheless will stay in any position of adjustment when in use. Another object is to provide resilient means for holding the brush 35 in various positions of adjustment, which will properly hold the brush in any desired position and remain operative for a long time, adapting itself to changes caused by any wear or enlargement at the aperture in 40 the cap where the brush slides. These and other objects I attain in the device herein-after described.

In the drawing forming part of this application,

45 Figure 1 is a vertical sectional view of a mucilage container or jar showing my device in use,

Fig. 2 is a vertical sectional view of the brush detached from the cap,

50 Fig. 3 is a sectional view taken on the line 3—3 of Fig. 2, and

Fig. 4 is a perspective view of the spring sleeve for holding the brush.

55 I have shown in the drawing a jar or container 1 such as is used for paste or mucilage and I have indicated a body 2 of mucilage

or paste therein. Part of the present device consists of a removable cap 3 which is adapted to serve as a cover to close the top of the jar to prevent the contents from 60 evaporating and to keep out dust. The cap 3 has a flange 4 which engages over the top edge of the jar and at the center of the cap there is an aperture 5 in which the shank of the brush may slide. 65

The brush consists of a body of bristles 6 held in the socket member 7, the upper portion of which is provided with a flange 8 to prevent the liquid from running along the shank when the brush is being used. There 70 is a rod or shank 9, preferably formed integral with the member 7 (these parts are preferably turned in wood) which is adapted to extend through the central aperture 5 of the cap, and its upper end extends into 75 the bore 10 of a knob or handle 11. There is a resilient sleeve 12 consisting of sheet metal bent into tubular or cylindrical form with its edges 13 lying in overlapping relation. In order to secure the proper spring 80 action in this sleeve it is necessary that these edges 13 overlap as shown herein.

In assembling the device the sleeve 12 is placed over the shank 9 and these members are then passed through the aperture 5 in 85 the cap from the bottom upwardly and the sleeve 12 is of such diameter, normally, as to make it necessary to compress it to permit it to be inserted through the aperture 5. When the sleeve and shank have been passed 90 through the cap the knob 11 is placed on the end of the shank 9, glue having been applied in the bore 10, so that the shank will be glued fast to the knob. The sleeve 12 is slightly larger than the shank 9 and 95 its upper end fits loosely in the counterbore 14 in the knob 11. The shank 9 forms the rigid or fixed member uniting the knob 11 and the brush member 7 and the sleeve 12 forms the spring means for adjustably holding the whole brush in position in the cap. The sleeve preferably has no great vertical displacement on the brush as it abuts at one end against the flange 8 and at the other end against the knob 11, but it is, so far as 100 the brush structure is concerned, free to expand and contract. When the brush is first assembled the aperture 5 will be of such size that the sleeve 12 will be compressed to nearly the size of the shank 9 in order to 105 pass through this aperture 5 and this will make the outer diameter of the sleeve less 110

than the counterbore 14. As the surface of the aperture 5 wears from long use the sleeve 12 will gradually expand within the counterbore 14 and within the aperture 5 and always maintain a frictional engagement with the cap sufficient to hold the brush in the desired position.

When the jar is nearly filled the brush will be raised in the cap so that the bristles 10 only will dip into the liquid or paste and the sleeve 12, engaging the cap, will maintain the brush in position. When the brush (together with the cap) is removed to apply some of the liquid to a surface the bristles 15 will carry some of the liquid but the remainder of the brush will be dry. As the liquid or paste is gradually consumed the brush will be adjusted from time to time to a lower position in the cap so that the 20 bristles will continue to dip into the liquid or paste. In the present device the sleeve 12 is free to expand to maintain sufficient friction at all times in the cap to hold the brush in position.

25 Having described my invention, what I claim is:

1. A device of the class described comprising a cap adapted to be applied to a bottle or jar to support a brush, and a brush 30 comprising a bristle portion, a shank slideable through said cap, an enlargement or knob on the upper end of said shank and an expandable sleeve surrounding said shank and frictionally engaging said cap and 35 adapted to hold the brush at various elevations in relation to the cap.

2. A device of the class described comprising a cap adapted to be applied to a

bottle or jar to support a brush, and a brush comprising a bristle portion, a shank slideable 40 through said cap, an enlargement or knob on the upper end of said shank, and an expandable, tubular sleeve having overlapping edges, said sleeve surrounding said shank, frictionally engaging said cap and adapted 45 to hold the brush at various elevations in relation to the cap.

3. A device of the class described comprising an apertured cap adapted to be applied to a bottle or jar to support a brush, 50 and a brush comprising a bristle portion, a shank slideable through said cap, an expandable sleeve surrounding said shank and adapted to frictionally engage the cap, and means for limiting the longitudinal movement of the sleeve in relation to the brush and adapted to permit the sleeve to expand. 55

4. A device of the class described comprising an apertured cap adapted to be applied to a bottle or jar to support a brush, 60 and a brush, comprising a bristle portion, a shank movable through said cap, an expandable sleeve surrounding said shank and frictionally engaging said cap, a knob having a bore in which the upper end of said shank 65 is secured and having a counterbore to receive the end of said sleeve and in which the sleeve is adapted to expand and contract, the longitudinal movement of the sleeve in relation to the brush being limited whereby 70 the sleeve engaging said cap will support the brush in different positions in relation to the cap.

Signed at the city, county and State of New York, this 15th day of June, 1920.

SALOMON VOS.
